CLAIM

We claim the ornamental design for a PCR multiwell plate, as shown and described.

DESCRIPTION

FIG. 1 is a top plan view of a PCR multiwell plate showing our new design;

FIG. 2 is an enlarged view of the encircled area shown in FIG. 1;

FIG. 3 is a front view thereof;

FIG. 4 is a side view thereof;

FIG. 5 is a bottom plan view thereof;

FIG. 6 is a perspective view thereof with one of the strip being separated; and,

FIG. 7 is an enlarged view of the top area shown in FIG. 6 after one strip has been separated.
